W. WAGNER

VACUUM BOTTLE HEATER

Filed Oct. 5, 1922

Inventor
W. Wagner

By *J. N. Bryant.*
Attorney

UNITED STATES PATENT OFFICE.

WALTER WAGNER, OF CHICAGO, ILLINOIS.

VACUUM-BOTTLE HEATER.

Application filed October 5, 1922. Serial No. 592,664.

To all whom it may concern:

Be it known that I, WALTER WAGNER, a citizen of Poland, residing at Chicago, in the county of Cook and State of Illinois, 5 have invented certain new and useful Improvements in Vacuum-Bottle Heaters, of which the following is a specification.

In my pending application filed March 23, 1922, bearing Serial No. 546,047 I have 10 disclosed a vacuum bottle of the all metal type, which bottle consists in brief of a double walled receptacle having a space therebetween for receiving a suitable filling, this space being evacuated in a manner 15 clearly and concisely set forth in a pending application filed by me of even date herewith. In this pending application, which is upon the method of manufacturing vacuum bottles of the type disclosed in my 20 first mentioned application, one stage of the process consists in subjecting the partially completed bottle to a high degree of heat preparatory to the subjecting of the bottle to the evacuation stage.

I have found that in the manufacture of 25 all metal vacuum bottles, it is almost an impossibility to properly produce a true vacuum between adjacent walls of the bottle while the same is in a cold state. This 30 fact being due, I believe, to the presence of moisture and gases in the pores of the metal. I have further discovered that by subjecting the walls of the bottle to a high degree of heat, preparatory to the evacuation process, 35 the pores of the metal will be entirely relieved of any moisture and gases, it being understood that the bottle is to be subjected to the evacuation process while in its heated state, at which time I have absolutely discovered that a true vacuum is resultant 40 between the spaced walls of the receptacle.

From the above it will be readily apparent 45 that the primary object of the present invention is the provision of a heater for subjecting partially completed vacuum bottles to a high degree of heat.

It is a further object of the invention to 50 provide a receptacle heater, which is comparatively simple in construction and one that will readily receive and support therein a vacuum bottle of the type disclosed in my pending application. It is, of course, to be understood that my device may be constructed to receive receptacles of a type 55 other than that shown by me without de-

parting from the spirit and scope of the present invention.

With the above and other objects in view, the invention consists of the novel form, 60 combination and arrangement of parts hereinafter more fully described, shown in the accompanying drawing and claimed.

In the drawing, wherein like reference characters designate corresponding parts 65 throughout,

The figure is a vertical cross sectional view of a heater constructed in accordance with the present invention showing a vacuum bottle supported therein in its partially completed state, the walls of the bottle adapted 70 to be heated to a high degree of temperature preparatory to the evacuation process.

In the drawing, I have disclosed a partially completed vacuum bottle designated 75 in general by the numeral 1 and consisting in brief of an inner receptacle 2 and an outer receptacle 3. As shown, each of these receptacles is made up of upper and lower sections, the meeting edges 2' and 3' respectively being suitably joined together in a 80 manner disclosed in my copending application filed on even date herewith. The bottle shown in the figure has a neck portion 4 formed thereon, and this neck portion is so constructed as to have an annular shoulder 5 slightly inwardly of the outer end thereof.

My heater includes a rigid support 6 which is of substantially U-shape in cross section, which support 6 has formed upon 85 the upper wall thereof a vertically disposed housing 7 of any desirable configuration being open at its top for permitting entrance of the vacuum bottle therein. Upon the interior of the housing 7 there is formed 90 or otherwise suitably secured a radially extending skeleton supporting shelf 8, which supporting shelf is provided with a central enlarged opening for allowing the bottle 1 to pass therethrough, the meeting edges 3' 100 of the sections forming the outer wall 3 of the bottle engaging upon the marginal edges of this opening for conveniently supporting the bottle within the housing 7. The bottom wall 7' of the housing is provided with 105 a central opening 9 and surrounding the edges of this opening and extending vertically therefrom is a supporting collar 10, the upper edge of which is adapted to engage the shouldered portion 5 of the neck 4 110

of the bottle for additionally supporting the bottle 1 within the housing 7. A flange 10' formed within the collar 10 provides an additional support for the bottle.

5 Within the housing 10 and slightly beneath the shelf support 8 is an annular shaped hollow burner member 11 suitably perforated as at 12, which burner entirely surrounds the bottle 1 within the housing. 10 The burner 11 is provided with an outlet nipple 13 for communication with a fuel inlet pipe 14.

Within the support 6 and extending vertically therein are other burner pipes 15 which extend upwardly through suitable apertures formed in the bottom wall 7' of the housing 7 whereby their outlet ends will be positioned within this housing for permitting the flame, therefrom, to impinge 20 against the adjacent side walls of the bottle 1. These vertically disposed burner pipes 15 are of any desired form and have communication as at 15' with fuel inlet pipes 16.

It will be readily understood, that a bottle 1 as shown in the drawing, which is supported within the housing 7 is so positioned with relation to the burner elements 11 and 15 as to have the walls of this bottle heated to the desired degree of heat, at which time any moisture or gases held in the pores of the metal forming the bottle will be suitably carried off, it being further noted that any moisture or gases which form upon the inner face of the inner receptacle 2 will by 35 gravity flow down and out through the opening 9 in the bottom wall 7' of the housing 7 and any gases or moisture that form between the inner and outer receptacles 2 and 3 respectively will consequently be 40 drawn off in the evacuation process fully described in my copending application.

What I claim as new is:—

1. In a heater for vacuum bottles of the type including a body portion having a central annular bead or flange projecting therefrom and having a neck portion with a shoulder formed thereon inwardly of the outer edge thereof, a housing, means within said housing for engaging said annular bead or flange portion of the bottle and the shoulder portion of the neck thereof for supporting the bottle in an inverted position within the housing, and burner elements within the housing supported adjacent the walls thereof.

2. In a heater chamber for vacuum bottles, a housing including a bottom wall, a supporting collar projecting upwardly therefrom, and a flange formed within said supporting collar.

3. In a heater for vacuum bottles, a housing including a bottom wall, a supporting collar projecting upwardly therefrom, a flange formed within said collar, and bur-

ner elements associated with said housing. 65

4. In a heater chamber for vacuum bottles, a housing comprising bottom and side walls, and means associated with each of said walls for supporting a bottle within said housing. 70

5. In a heater for vacuum bottles of the type including a body portion having a central annular bead projecting therefrom, a housing, and means within said housing for engaging said bead for supporting the 75 bottle in an inverted position within said housing.

6. In a heater for vacuum bottles of the type having a neck portion with a shoulder formed thereon, a housing including a bottom wall, and means within said housing for engaging said shoulder portion for supporting the bottle in an inverted position within the housing, said means including a collar formed in said bottom wall of the 85 housing.

7. In a heater for vacuum bottles, a housing having a side wall, a shelf support carried by said wall for holding the bottle in an inverted position, and a burner element 90 positioned adjacent said side wall.

8. In a heater for vacuum bottles, a housing including a side wall, and a burner of an annular and hollow construction within said housing adapted to entirely surround a 95 bottle positioned within said housing, said burner being mounted upon said side wall.

9. In a heater for vacuum bottles, a housing adapted for receiving a bottle and having a side wall, a burner of annular construction mounted upon said side wall and provided with perforations for the purposes set forth. 100

10. In a heater for vacuum bottles, a housing adapted for receiving a bottle and comprising a bottom wall and a side wall, means associated with said bottom wall providing an upright support for the bottle, and means associated with said side wall providing a lateral support for the bottle. 110

11. In a heater for vacuum bottles of the type including a body portion having a central annular bead projecting therefrom, a housing, and an annular shelf therewithin for engaging said bead for laterally supporting the bottle in an inverted position within the housing. 115

12. In a heater for vacuum bottles, a housing including a side and bottom walls, and burner associated with each of said 120 walls.

13. In a heater for vacuum bottles, a cylindrical housing having an open end, and burner elements associated with all of the walls of said housing. 125

In testimony whereof I affix my signature.

WALTER WAGNER
